MEANS FOR CONTROLLING THE FLUID
LEVEL IN A DRILL STRING

Robert E. Tinsley, Ventura, Calif.

Application April 1, 1939, Serial No. 265,408

7 Claims. (Cl. 255—1)

This invention relates to means for controlling the mud, or other fluid, level inside a well and drill string after circulation has been stopped and the drill string is being removed from or inserted in the well.

During a rotary drilling operation the mud or other drilling fluid that is being circulated down the drill string, becomes loaded with detritus and cuttings from the bit, and consequently the mud on the outside of the drill string is much heavier than the mud on the inside, and this causes the mud on the inside of the drill tubing to rise to a considerably higher level than the mud on the outside, and sometimes the mud in the tool string may extend almost the height of a stand of pipe above the point at which the stand is disconnected or "broken out," which is usually slightly above the derrick floor. Consequently, when the drill pipe is disconnected at the floor of the derrick, this mud will spill out as the joint is disconnected, and flow out over the top of the drill pipe still remaining in the well. This mud covers the derrick floor and is of course very disagreeable for the rough-necks working on the well. The slippery mud also greatly increases the chance of accidents occurring. But important also, is the loss of the mud.

In other cases where the level of the mud in the drill string is not above the level of the derrick floor, nevertheless in the usual pulling of a drill string, considerable mud adheres to the inside of each stand of pipe as it is pulled, and the loss of this adhering mud will lower the mud level and reduce the hydrostatic pressure of the mud to such an extent that blow-outs of mud may occur. It also would reduce the mud pressure on the sides of the well hole, which should be avoided.

It is desirable that the well be kept full of fluid while the drill string is being pulled, in order to prevent caving of the walls which might occur if the fluid level were allowed to drop, which it normally would do. The well crew, on the other hand, prefer to let the fluid level drop far enough so that when the drill string is pulled, the sections, as they are disconnected, will be dry.

One of the objects of this invention is to provide a simple method and means for overcoming these difficulties.

A further object of the invention is to provide a simple method and means for preventing the mud level in the drill string from rising above the derrick floor, and to conserve the mud and prevent loss of the same in pulling operations.

A further object of the invention is to enable

a pulling operation to be accomplished with a minimum quantity of mud, but at the same time maintaining the normal mud pressure on the well.

A further object of the invention is to provide a simple method and means for wiping the mud internally from each stand of pipe as the same is pulled up into the derrick.

In practicing the invention, I provide a loose piston that I insert in the tool string. This piston loads the mud within the drill string and depresses the level of the mud therein below the derrick floor. In a pulling job, if the tubing has become broken, it is evident that when the break in the tubing reaches this piston, the piston would get out of the tubing and become lost in the well, necessitating a real fishing job to recover the same. One of the objects of this invention is to provide simple means for preventing the loss of the loose piston, and to enable it to be automatically caught and pulled up with the lower broken end of the tubing.

Further objects of the invention will appear hereinafter.

The invention consists in the novel method and means, the features of which contribute to produce an efficient method and means for controlling the mud in tubing as the same is pulled, all of which is described in the following specification and particularly set forth in the claims.

30 In the drawing:

Fig. 1 is a side elevation of a derrick showing the upper end of a tube string in section, and illustrating my device and the method of employing the same.

35 Fig. 2 is a vertical section through the device upon a larger scale, and illustrating the same in detail.

Fig. 3 is a vertical section through a portion of a drill string in the vicinity of the piston, and 40 showing a portion of this device in section. This view illustrates means for automatically catching the device to enable it to be withdrawn with the broken end of the tubing. This view shows the device in its set position as it would have before being reached by a break in the tubing.

Fig. 4 is a view similar to Fig. 3, but illustrating the automatic catching device in its operating position after the break in the tubing has reached the location of the piston.

50 In practicing the invention, I provide a loose plug or piston 1 that I insert into the bore of the tubing 2. This piston yieldingly fills the bore of the tubing and packs the same so as to hold the mud below it. In other words, it is supported on, but not floating on, the drilling fluid or mud.

Hence the weight of the piston loads the mud in the tubing.

The piston 1, which may also be called a wiper, or swab, consists of a tubular body 4, the lower end of which is threaded into a weight section 5 to give the necessary weight to it.

The body 4 is provided with a wiper sleeve 9 preferably in the form of a soft sleeve resembling a swab but preferably provided with a tapered lip 10 at its lower end. The upper end of this sleeve is provided with a metal ferrule or binder 11 that seats against the lower end of the sub 8. This binder prevents any possibility of the soft sleeve 9 being dislocated when dropped into the tubing 2.

When the tubing is pulled with this piston and wiper device in the tubing, the weight of the wiper depresses the mud level inside the tubing so that by the time the stand of tubing is broken out, the mud level is at or below the point at which the drill string stands are disconnected. In the present instance this would be at the derrick floor. The piston maintains the mud pressure in the well; and when a stand of the tubing is pulled up into the derrick to be broken out, the lip 10 and the sleeve body 4 wipe the adhering mud back off the wall. Hence there is very little mud if any in the stand when broken out, thereby preventing loss of mud, and enabling the pulling job to be a comparatively clean one. This can be accomplished while the mud pumps are running slowly so as to keep the hole full of fluid while the tubing is being withdrawn from the well.

In order to enable the wiper to be retrieved when desired, its upper end may be provided with an undercut head 13 that can be caught by an overshot fishing tool on a line from the mouth of the well.

As a safety feature to enable circulation to be resumed if necessary, a downwardly opening check valve 14 is provided at the lower end of the body 4, that permits such circulation. When this occurs, of course, the plug 1 will sink to the bottom of the tool string, but this cannot shut off circulation of mud to the drill because I provide the lower end of the bottom section 5 with a transverse recess 5'. This prevents the lower end from plugging the mud outlet at the drill bit.

The weight section of the device is a metal body with ports 6 that communicate with the interior of the body and conduct downcoming mud out into the tubing. Inlet ports 7 in a sub 8 carried in the upper end of the body 4, co-operate with the port 1 to enable mud to be circulated down from above if mud circulation has to be resumed.

The weight necessary for the device can be reduced by placing the packing sleeve 9 at the lower end instead of at the upper end. In that case the mass of the metal would not be immersed in the mud and would consequently have more dead weight. Of course, the solid section 5 can have any length necessary to give the piston 1 the requisite weight.

The weight of the piston 1 depresses the mud level considerably. No mud can be thrown out at the well's mouth, as the piston will not rise sufficiently to permit this.

In Figs. 3 and 4 I illustrate an automatic catching device to prevent the piston 1 from becoming lost in the well if a break has occurred in the drill string that is being pulled. For this purpose I provide the weight section 5 of the device with a tapered slip 15 that is received in a socket 16 cut in its side face and

seating against an inclined face 17. This slip is normally held against relative upward movement in the slip socket by means of a long spring 18, the upper end of which is secured at 19 to the side of the part 5, and extends a considerable distance below the socket 16; at the socket it is provided with a nib or shoulder 20 that engages the upper end of the slip. This spring 18 tends by its resiliency to force its lower end outwardly against the side of the tubing 2. A pair of small leaf springs 21 attached to the slip, rub on the inner face of the tubing. In pulling the tubing, if a break 22 has occurred in the tubing, when this break passes above the lower end of the spring 18, the spring forces itself outwardly, and in this way releases the upper end of the slip 15 from the shoulder or nib 20. Due to the release of the mud at the broken point 22, the piston will be unsupported and will start to fall. As it does so, the slip 15 will jam on the inclined face 16 and lock the piston into the lower end of the tubing (see Fig. 4). Hence if the broken end of the tubing is pulled up, the piston 1 will be recovered with it.

It is obvious that this piston 1 may be employed in a drill string for keeping down the fluid level within it while running the drill string down into the well.

Many other embodiments of this invention may be resorted to without departing from the spirit of the invention.

What I claim is:

1. In a drilled well, the combination of a tubular tool string carrying mud with a weighted piston filling the bore of the tool string freely movable within the same and resting on the mud, said piston operating by its own weight to depress the mud level within the tool string, and also operating to wipe the mud from the interior of the tubing when the same is being pulled; and automatic means for catching the piston in the tool string brought into action by a break in the tool string when the break arrives at the piston.

2. In a drilled well, the combination of a tubular tool string carrying mud with a weighted piston filling the bore of the tool string freely movable within the same and resting on the mud, said piston operating by its own weight to depress the mud level within the tool string, and also operating to wipe the mud from the interior of the tubing when the same is being pulled; said piston having a slip mounted in the side thereof with means carried on the slip for frictionally engaging the wall of the tool string, and a resilient member carried by the piston extending down below the same and having means for normally engaging the slip to prevent the same from operating, said resilient means operating when a break arrives at the piston, to swing outwardly at its lower end and thereby release the slip, said slip cooperating with the piston thereafter to catch the piston in the tool string.

3. In a drilled well, the combination of a tubular tool-string carrying mud, with a packed piston constructed so that it lies within and is freely movable in the tool-string, filling the bore of the tool-string, and resting, and supported upon, the mud, so as to depress the mud level.

4. In a drilled well, with a hoist for pulling and "breaking out" tubing, the combination of a tubular tool-string carrying mud, a loose freely movable piston having a packing sleeve carried in the bore of the tool-string and resting on the mud, and normally depressing the mud level be-

low the point at which the drill string is disconnected when pulling the same, said piston operating as a wiper when the tubing is pulled to prevent mud from being carried up and spilled at the well's mouth.

5. In a drilled well, with a hoist for pulling and "breaking out" tubing, the combination of a tubular tool-string carrying mud, a loose freely movable piston having a packing sleeve carried in the bore of the tool-string and resting on the mud, and normally depressing the mud level below the point at which the drill string is disconnected when pulling the same, said piston operating as a wiper when the tubing is pulled to prevent mud from being carried up to the well's mouth and spilled at the well's mouth, said piston having a duct leading into the same above the packing sleeve, and a downwardly opening check valve in said duct for conducting downwardly circulating mud past the packing sleeve.

6. In a drilled well, with a hoist for pulling and "breaking out" tubing, the combination of a tubular tool-string carrying mud, a loose freely movable piston having a packing sleeve carried in the bore of the tool-string and resting on the mud, and normally depressing the mud level below the point at which the drill string is dis-

connected when pulling the same, said piston operating as a wiper when the tubing is pulled to prevent mud from being carried up and spilled at the well's mouth, said piston having a duct leading into the same above the packing sleeve, and a downwardly opening check valve in said duct for conducting downwardly circulating mud past the packing sleeve, the bottom end of said piston having a transverse recess operating to prevent the lower end of the piston from plugging the mud outlet at the drill bit if the piston should descend to the lower end of the drill string.

7. A device for removing drilling fluid from a string of drill pipe being pulled upwardly through a derrick floor comprising a body member slightly smaller in diameter than the inside diameter of said pipe, resilient means surrounding said body member and adapted to contact the inner surface of said pipe so as to fill the annular space between said body member and the inner surface of said pipe, said device having sufficient weight to force drilling fluid downwardly through said pipe string and to maintain the level of the fluid below said derrick floor while the pipe string is being raised.
